(57) **CLAIM**

The ornamental design for a compact disk container, as shown and described.

DESCRIPTION

FIG. 1 is a perspective view of a compact disk container in accordance with an embodiment of my new design.

FIG. 2 is a top plan view thereof.

FIG. 3 is a bottom plan view thereof.

FIG. 4 is a left elevation view thereof.

FIG. 5 is a right elevation view thereof.

FIG. 6 is a front elevation view thereof.

FIG. 7 is a rear elevation view thereof; and,

FIG. 8 is another perspective view of the compact disk container of FIG. 1, in an alternate configuration.
